INVENTOR
BY *Victor J. Evans*

ATTORNEY

WITNESS:

UNITED STATES PATENT OFFICE.

JOHN A. PETERSON, OF KANSAS CITY, MISSOURI, ASSIGNOR TO CLYDE J. TURNER AND JAMES H. YOUNG, BOTH OF KANSAS CITY, MISSOURI.

VAPOR MOISTENER.

Application filed February 16, 1926. Serial No. 88,628.

This invention relates to an attachment for a motor vehicle, the general object of the invention being to provide means for introducing air and moisture into the intake manifold of the motor of the vehicle to increase the efficiency of the motor.

Another object of the invention is to provide means whereby the air currents will thoroughly break up the drops of moisture and be mixed with the same before reaching the manifold.

Another object of the invention is to provide means for controlling the air and moisture supply from a point adjacent the driver's seat.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a view showing the invention in use upon the motor of a vehicle.

Figure 2 is an enlarged view of the device itself.

Figure 3 is a view taken at right angles to Figure 2.

Figure 4 is a section on line 4—4 of Figure 3.

Figure 5 is a section on line 5—5 of Figure 3.

Figure 6 is a section on line 6—6 of Figure 3.

In these views I have shown a two part cylinder, the parts of which are indicated by the reference numerals 1 and 1^a respectively, and are connected together by the bolts 2 which pass through the ears 3 formed on the abutting ends of the two parts. A suitable gasket can be placed between the two parts to insure an air tight connection.

A partition 4 is arranged in one part and this partition is formed with a valve seat 50 which is engaged by a valve 5, the stem of which passes through one end of the casing where it receives a spring 6 which bears against a nut 7 on the stem so that the valve is normally held to its seat and thus communication between the two parts is closed.

The outer part is provided with air ports 8 which are normally covered by a hinged member 9 which is provided with a spring 10 for holding it closed. A hand operated member 11 is placed on the instrument board 60 A of the vehicle and this member is connected by a cable 12 with the member 9 so that by pulling upon the member 11 the member 9 will be moved to open position against the action of the spring 10 and thus air can pass 65 into that part of the cylinder in rear of the valve 5. A nipple 13 is formed on the inner end of the cylinder and is adapted to be threaded into a hole formed in the inlet manifold B of the motor and an L-shaped 70 member 14 is integrally formed with the cylinder and has its inner end connected with the inner end of the cylinder, in alignment with the nipple, and said member passes through the side of the cylinder with its 75 outer end threaded to receive a coupling 15. A passage 16 passes through said member 14, the end of the cylinder and the nipple and communicates with a recess 17 formed in the outer end of the nipple. A plurality of 80 air passages 18 extend through the inner end of the cylinder and the nipple with the outer ends in communication with the recess 17 and their inner ends in communication with the interior of the cylinder. These air passages 85 18 are formed around that part of the passage 16 in the nipple and are arranged in the shape of a cone with the inner ends surrounding the inner end of the member 14 and the outer ends surrounding the outlet 80 end of the passage 16. The coupling 15 is connected with a needle valve casing 19 which is in turn connected by the tubing 20 with the water jacket in the top of the motor so that water will enter the casing 19 from 95 the cooling system of the motor. The needle valve 21 controls the flow of water into the casing and this needle valve can be adjusted by means of the forked rod 22 having its forked end engaging holes in the head 23 of 100 the valve and its headed end passing through the instrument board A.

From the foregoing it will be seen that when the operator opens the member 9 by means of the member 11 and the cable 12 105 and adjusts the valve 19 by means of the forked rod 22 to permit water to enter the device, the suction created by the moving pistons will draw the water from the needle valve casing through the passage 16 into the 110

recess 17 so that the moisture will enter the cylinders through the manifold B. This suction will also open the valve 5 and cause air to pass through the ports 8 into the inner 5 part of the cylinder and then this air will pass through the passages 18 and the streams of air leaving these passages will encounter the water leaving the passage 16 and thus the water will be broken up in minute particles and thoroughly mixed with the air so that the air will be moistened and thus mixed with the explosive charge in the manifold B so that the efficiency of the motor is increased. The operator can control both the 15 flow of air and the flow of water from the instrument board.

It is thought from the foregoing description that the advantages and novel features of my invention will be readily apparent.

20 I desire it to be understood that I may make changes in the construction and in the combination and arrangement of the several parts, provided that such changes fall within the scope of the appended claim.

25 What I claim is:—

An attachment for internal combustion engines, comprising a cylinder, a partition

therein and being formed with a valve seat, a spring controlled valve engaging the seat, said cylinder having air ports formed in the 30 cylindrical portion thereof to the rear of the valve, a spring actuated cover for the ports, a nipple formed with said cylinder at the inner end thereof for connecting the cylinder with the inlet manifold of an internal combustion engine of a vehicle and being provided with air passages extending therethrough and the inner end of the cylinder respectively, an L-shaped member having its inner end formed with the inner end of the 40 cylinder and its other end portion passing through the cylindrical wall thereof, said L-shaped member having a passage therein in communication with said nipple, a casing in communication with said member and the 45 water jacket of the internal combustion engine, means for controlling said communication arranged in said casing, means for operating the last mentioned means and for opening the spring actuated cover from the 50 dash of the vehicle.

In testimony whereof I affix my signature.

JOHN A. PETERSON.
